UNITED STATES PATENT OFFICE

FRANK L. GORMLEY, OF BOSTON, MASSACHUSETTS.

LIFTING-JACK.

No. 921,235.

Specification of Letters Patent.

Patented May 11, 1909.

Application filed November 27, 1908. Serial No. 464,787.

To all whom it may concern:

Be it known that I, FRANK L. GORMLEY, a citizen of the United States of America, and a resident of Boston, in the county of Suffolk 5 and State of Massachusetts, have invented certain new and useful Improvements in Lifting-Jacks, of which the following is a specification.

This invention relates to lifting jacks and 10 particularly to that class of jacks which are known as ratchet screw jacks, and has for its object the provision of a means whereby the movable member is prevented from being accidentally lowered under a heavy load.

15 The invention consists in providing a nut, which is preferably divided, with some means, as, for instance, a wedge-shaped shoulder, which, when the movable member of the jack to which the screw is secured is 20 subjected to any weight, will force the nut into firm contact with the threads of the screw and prevent the screw from turning in said nut, except when power is applied to the screw itself to cause a rotation thereof.

25 The invention consists in certain novel features of construction and arrangement of parts which will be readily understood by reference to the description of the drawings and to the claims hereinafter given.

30 Of the drawings: Figure 1 represents a horizontal section of a lifting jack embodying the features of this invention, the cutting plane being on line 1—1 on Fig. 2. Fig. 2 represents a vertical section of the same, the 35 cutting plane being on line 2—2 on Fig. 1. Fig. 3 represents a section of the device for rotating the screw, the section being on line 3—3 on Fig. 1. Fig. 4 represents a horizontal section of the jack, the cutting plane being on line 4—4 on Fig. 2, and Figs. 5 and 6 represent, respectively, a plan and an elevation of the divided nut.

40 Similar characters designate like parts throughout the several figures of the drawings.

45 In the drawings, 10 represents a suitable base supporting a stationary standard 11 over the outer periphery of which is fitted a movable sleeve 12 to the upper end of which 50 is threaded a head 13. In the upper inner end of the head 13 is mounted a plate 14 provided with an annular groove 15 and a central bearing for the reduced shank 16 of the revoluble threaded member or screw 17.

Keyed to the reduced shank 16 of the 55 screw 17 is a gear 18 meshing with a gear 19 formed upon or secured to a revoluble shaft 20 mounted in a lateral bearing 21 formed upon the plate 22 secured to the head 13. The gear 18 is provided with an annular 60 groove 15* corresponding to the groove 15 and in these grooves 15 and 15* are placed a plurality of balls 18* to reduce the friction.

On the reduced end of the shaft 20 is keyed or otherwise secured a ratchet 23 between the 65 two arms 24 of a bifurcated member 25. This bifurcated member 25 is provided with an operating handle 26 and in ears 27 formed upon the arms 24 is secured a pin 28 upon which is mounted the double acting pawl 29, 70 one of the teeth of which is retained in engagement with the teeth of the ratchet 23 by means of the locking bolt 30 mounted in a socket in the member 25 and forced outwardly by means of the spring 31. The bolt 75 30 is prevented from turning by means of the screw 32 engaging a longitudinal slot in the bolt 30 as indicated in Fig. 3 and the outer end of said bolt is V-shaped so that the point thereof will engage either the face 33 of the 80 pawl 29 to cause one of the teeth thereof to engage with the ratchet wheel 23 or with the face 34 to cause the other tooth of the pawl to engage with said ratchet wheel, the particular tooth to be engaged with the ratchet 85 wheel 23 being determined by the direction in which it is desired that the gear 19 shall be turned. It is obvious that by giving the handle 26 an up-and-down or pump handle motion with the pawl 29 in the position 90 shown in Fig. 3, the gears 18 and 19 will be rotated so as to cause the screw 17 to turn within the nut 35 to cause a lifting of the head 13 relative to the standard 11. It is also obvious that when the position of the 95 double-acting pawl 29 is reversed and the V-shaped end of the locking bolt 13 is in engagement with the face 34 of said pawl and the same motion is accorded to the handle 100 26, a reverse motion will be accorded to the gears 18 and 19 and the screw 17 will be turned in its nut 35 to cause a lowering of the head 13.

105 The jack thus far described is of well-known construction and forms no part of the present invention. It has been found, however, that when the threads of the screw 17 are of a certain coarse pitch and the head 13

is subjected to the weight of a heavy load, sometimes the screw 17 will turn in the nut 35 and cause the accidental lowering of the head relative to the standard 11. This accidental lowering of the lifting jack under a heavy load is dangerous and obviously objectionable. The present invention is for the purpose of overcoming this difficulty and in order to effect a positive locking of the head 13 in any adjusted position so that it will be impossible for it to be accidentally lowered under a heavy load the nut 35 is divided as indicated in Figs. 4 and 5, at 36, while the outer periphery of said nut is provided with a conical shaped cam shoulder 37, this shoulder 37 normally resting upon the inclined face of the upper end of a ring 38 in a socket 39 in the upper end of the standard 11.

Each of the parts of the divided nut 35 is provided with slots 40 cut into the periphery and extending longitudinally thereof to its upper end. The socket 39 has similar slots cut into the upper end of the standard 11 and into these slots are inserted keys 41, each of which is half embedded in the slot in the standard 11 while the other half is in one of the slots 40 of the nut 35. These keys 41 will prevent the nut from turning during the rotation of the screw 17 while at the same time the two parts of the nut 35 are free to move endwise or longitudinally of the axis of the screw 17. Threaded to the upper end of the standard 11 is a cup-shaped member 42 which extends over the nut 35 and the keys 41 and prevents them from becoming displaced.

In the operation of the invention the shoulder 37 of the two parts of the nut 35 normally rests upon the upper end of the ring 38 and when the handle 26 is operated the screw 17 may be rotated in the nut 35 in either direction to cause a lifting or lowering of the head 13. Should, however, the head 13 be subjected to a heavy load the weight of which is sufficient to cause a tendency of the screw 17 to accidentally rotate in the nut 35, the downward pressure of the screw upon the two parts of the nut 35 will cause the inclined shoulder 37 to so act upon the upper ends of the ring 38 to force these two parts toward each other and to be tightly clamped upon the screw 17 so that it would be impossible for the screw to turn therein, thereby absolutely preventing the accidental lowering of the head under a heavy load. Should it be desired to lower the load, the position of the pawl 29 is reversed and the screw 17 is rotated in the nut 35 in the opposite direction by means of the handle 26. As soon as the head has been lowered a desired distance and the operation of the handle 26 has ceased the nut 35 will immediately again clamp the screw 17 and prevent any accidental rotation thereof.

It is believed the operation and many ad-

vantages of a lifting jack such as herein described will be fully understood from the foregoing.

Having thus described my invention, I claim:

1. In a lifting jack, the combination of a stationary member; a movable member thereon; a screw for said movable member; means for rotating said screw; a nut in said stationary member; and means operable under a load to clamp said nut upon said screw. 75

2. In a lifting jack, the combination of a stationary member; a movable member thereon; a screw for said movable member; means for rotating said screw; a divided nut in said stationary member; and means operable under a load to clamp said nut upon said screw. 80

3. In a lifting jack, the combination of a stationary member; a movable member thereon; a screw for said movable member; means for rotating said screw; a nut in said stationary member having a cam-shaped shoulder; and a ring surrounding said nut and adapted to act on said shoulder to clamp said nut upon said screw when said nut is subjected to downward pressure. 85

4. In a lifting jack, the combination of a stationary member; a movable member thereon; a screw for said movable member; means for rotating said screw; a divided nut in said stationary member having a cam-shaped shoulder; and a ring surrounding said nut and adapted to act on said shoulder to clamp said nut upon said screw when said nut is subjected to downward pressure. 90

5. In a lifting jack, the combination of a stationary member; a movable member thereon; a screw for said movable member; means for rotating said screw; a nut in said stationary member having a cam-shaped shoulder; a ring surrounding said nut and adapted to act on said shoulder to clamp said nut upon said screw when said nut is subjected to downward pressure; and means for preventing the rotation of said nut and ring. 105

6. In a lifting jack, the combination of a stationary member; a movable member thereon; a screw for said movable member; means for rotating said screw; a nut in said stationary member having a cam-shaped shoulder; a ring surrounding said nut and provided with a wedge-shaped edge adapted to act on said shoulder to clamp said nut upon said screw when said nut is subjected to downward pressure; and means for preventing the rotation of said nut and ring. 115

7. In a lifting jack, the combination of a stationary member provided with a wedge shoulder; a movable member thereon; a screw for said movable member; a nut therefore in said stationary member provided with a cam-shaped shoulder normally resting on said wedge shoulder; and means for preventing said nut from rotating while per- 125

mitting the end movement thereof under a load to clamp said nut on said screw.

8. In a lifting jack, the combination of a stationary member provided with a wedge shoulder; a movable member thereon; a screw for said movable member; a divided nut therefor in said stationary member provided with a cam-shaped shoulder normally resting on said wedge shoulder; and means 10 for preventing said nut from rotating while permitting the end movement thereof under a load to clamp said nut on said screw.
9. In a lifting jack, the combination of a stationary member provided with a wedge shoulder; a movable member thereon; a screw for said movable member; a nut therefor in said stationary member provided with a cam-shaped shoulder normally resting on said wedge shoulder and having slots 15 extending longitudinally of its periphery; and keys mounted in said stationary member and extending into said slots.

10. In a lifting jack, the combination of a stationary member provided with a wedge shoulder; a movable member thereon; a screw for said movable member; a nut therefor in said stationary member provided with a cam-shaped shoulder normally resting on said wedge shoulder and having slots 20 extending longitudinally of its periphery; keys mounted in said stationary member and extending into said slots; and a cap threaded to the upper end of said stationary member to prevent the displacement of said keys, 25 and the upward movement of said nut.

11. The combination of a stationary mem-

ber; a nut in said stationary member; a revolute screw in said nut; a movable member supported by said screw; and means operable under a load to clamp said nut upon 40 said screw.

12. The combination of a stationary member; a divided nut in said stationary member; a revolute screw in said nut; a movable member supported by said screw; 45 and means operable under a load to clamp said nut upon said screw.

13. The combination of a stationary member; a divided nut in said stationary member having a cam shoulder; a revolute screw in 50 said nut; a movable member supported by said screw; and a ring surrounding said nut and adapted to act on said shoulder to clamp said nut upon said screw when said nut is subjected to downward pressure. 55

14. The combination of a stationary member; a divided nut in said stationary member having a cam shoulder; a revolute screw in 60 said nut; a movable member supported by said screw; a ring surrounding said nut and adapted to act on said shoulder to clamp said nut upon said screw when said nut is subjected to downward pressure; and means for preventing the rotation of said nut and ring. 65
